UNITED STATES PATENT OFFICE.

RUDOLF LOEB, OF JENKINTOWN, PENNSYLVANIA.

EMBROIDERED EDGING.

1,162,498.

Specification of Letters Patent.

Patented Nov. 30, 1915.

Application filed January 9, 1915. Serial No. 1,326.

To all whom it may concern:

Be it known that I, RUDOLF LOEB, a citizen of the United States, and a resident of Jenkintown, Montgomery county, Pennsylvania, have invented an Improved Embroidered Edging, of which the following is a specification.

My invention relates to mechanically produced embroidery, and consists of an improved ornamental edging for fabrics in the shape of scallops or festoons produced by an "overlock" sewing machine in which the fabric is automatically trimmed ahead of the stitching operation, but in which instead of a straight overlock stitch or over-seam edging, I am able to produce a scalloped or indented edge having a substantially regular inner marginal line for the stitching which passes through the fabric, between which substantially regular line of stitching and the outer scalloped or indented margin continuous stitches or loops of thread of varying length in regular order are disposed. In the formation of such indented or scalloped and stitched edge, the fabric is not cut away to follow the finished contour of the same, but at the points where the shorter stitches or loops of thread are laid, such fabric is rolled or folded which additionally produces a slightly stuffed effect for the said ornamental edge. These and other features of my invention are more fully described hereinafter, reference being had to the accompanying drawings, in which:

Figure 1, is a perspective view of the ornamental embroidery forming the subject of my invention; Fig. 2, is an enlarged plan view of the obverse side of the embroidered edging; Fig. 3, is an enlarged plan view of the reverse side of the embroidered edging; Fig. 4, is a sectional view on the line 4-4, Fig. 2; Fig. 5, is a sectional view on the line 5-5, Fig. 2; Fig. 6, is a perspective view of part of the mechanism employed in forming my improved embroidery edging, and Figs. 7, 8 and 9, are views of details of such mechanism.

In the operation of an overlock stitching machine (my invention has been carried out with a machine of the Wilcox & Gibbs type, although it will be understood that other machines of the same type may be employed,) means are provided to regulate the length of the stitches and determine the width of the edging or the position in which the

stitches passing through the fabric shall occupy.

In the operation of laying short and long stitches in the formation of the improved embroidery edging constituting my invention, I provide a movable member having a pointed end over which the stitches are formed, which member is moved at regular intervals with relation to the point at which the stitches are being formed, with the result that short stitches will be formed over the point of such member when moved in one direction, said stitches gradually lengthening to the full sized stitches over the main body or heel of such stitch member; which stitches are gradually shortened as the stitch member is moved in the opposite direction.

In the drawings, in which I have represented an overlock or overseam stitched edging form of two threads, 1 represents the fabric, 2 one thread and 3 the other. The thread 2 has a plurality of loops on each side of the fabric; those indicated at 2^a lying close against the fabric, while those indicated at 2^b extend to the margin of the fabric from said loops 2^a. The several loops 2^a and 2^b of the thread 2 are caught by the thread 3 which is looped back and forth on one face of the fabric in the manner clearly indicated in the drawings.

The stitches are formed over a tapering or pointed member 5 which is reciprocated back and forth with respect to the point at which the stitches are formed; the short stitches being formed over the point of the same while the long stitches are formed over the thicker heel portion thereof. Movement of this member 5 may be effected by a lever 6 having a cam groove 7 in which moves a roller 8 actuated from a suitable movable part of the machine.

In the formation of the short and long stitches, it is, of course, necessary to alter at regular intervals the amount of thread fed to the stitch forming elements, and hence I provide special tension means for the several threads; the operation of such tension means coördinating with the movements of the stitch forming element, so that while sufficient thread will be provided for the longer stitches, the supply of the same will be cut down for the shorter stitches. This tension may be controlled by a lever 9 moved in consonance with the lever 6 actuating said member 5.

As noted above, these stitches are formed

immediately after a cutting operation which shears away a portion of the fabric, and this cutting action may proceed along a regular or straight line that is parallel or substantially parallel to the line of stitches indicated by the loops 2^a which pass through the fabric adjacent the embroidered edge or margin of the same, and hence it becomes necessary to dispose of small portions of the fabric adjacent each indented portion of the scallops in order that the short stitches may be properly formed and accommodated. To accomplish this result, the fabric is rolled or folded at intervals by the stitches themselves; the rolled or folded portions serving to stuff the shorter stitches and enhance the ornamental value of the embroidered edge.

While I have shown and described my improved embroidery edging as made with a plurality of threads, it will be understood that an overlock or overseam stitch of the buttonhole type formed of a single thread such, for instance, as illustrated in the patent to Willcox & Borton, No. 472,094, may be employed without departing from my invention, and my claims are to be read as covering broadly an overlock or overseam stitch binding the edge of a fabric with short and long stitches forming an indented or scalloped edge, whether such stitches are formed of a single thread or a plurality of threads.

I claim:

1. As a new article of manufacture, an overseam edging comprising a plurality of stitches overlying and binding the edge of a fabric; the several stitches being disposed on both faces of the fabric and being graduated in length with respect to a substantially straight inner margin or base line whereby a scalloped or indented outer margin is provided.

2. As a new article of manufacture, an overseam edging made up of a pair of threads, one thread being disposed in the form of short loops on one face of the fabric to form a substantially straight inner margin or base line and longer loops on the other face of the fabric, while the second thread comprises a plurality of looped portions caught on one face only of the fabric by the respective loops of the first-mentioned thread; the longer loops of the several threads being disposed on both faces of the fabric between the outer edge of the fabric and the base line and being graduated in length whereby a scalloped or indented ornamental margin is provided.

3. As a new article of manufacture, an

overseam edging made up of a pair of threads, one of which threads has loops on both faces of the fabric, one set of said loops being short and lying close to the surface of the fabric and forming a substantially straight line, and the other set being relatively longer, the second thread comprising a plurality of looped portions disposed on the face of the fabric opposite the face having the longer loops of the first-mentioned thread by both sets of loops of the first-mentioned thread; the longer loops of the first-mentioned thread and the loops of the second thread being graduated in length in substantially regular order whereby a scalloped or indented ornamental margin is provided.

4. As a new article of manufacture, an overseam comprising a plurality of stitches binding the edge of a fabric; the several stitches being graduated in length whereby a scalloped or indented margin is provided, and the fabric at the indented portion of the scallops, being rolled and serving to stuff the stitches inclosing the same at such point.

5. As a new article of manufacture, an overseam comprising a plurality of threads each having interengaging stitches binding the edge of a fabric; the several stitches being graduated in length whereby a scalloped or indented margin is provided, and the fabric at the indented portion of the scallops being rolled and serving to stuff the stitches inclosing the same at such point.

6. As a new article of manufacture, an overseam made up of a plurality of threads, one thread being disposed in the form of short loops on one face of the fabric to form a substantially straight inner margin or base line and longer loops on the other face of the fabric, while the other thread comprises a plurality of looped portions caught on one face of the fabric by the respective loops of the first-mentioned thread; the several stitches on both faces of the fabric between the outer edge of the fabric and the base line being graduated in length whereby a scalloped or indented ornamental margin is provided, and the fabric at the indented portion of the scallops being rolled and serving to stuff the stitches inclosing the same at such point.

In testimony whereof, I have signed my name to this specification, in the presence of two subscribing witnesses.

RUDOLF LOEB.
